222,310

COMBINATION BARBECUE PIT, GRILL, BOILER AND OVEN

Malcolm A. Zaunbrecher, 1007 W. Texas Ave.,
Rayne, La. 76578

Filed Aug. 11, 1970, Ser. No. 24,428

Term of patent 14 years

Int. Cl. D7—02

U.S. Cl. D81—10

FIG. 1 is an orthographic front elevation of a combination barbecue pit, grill, boiler and oven showing my new design;

FIG. 2 is a top orthographic view thereof;

FIG. 3 is an orthographic right side elevation thereof;

FIG. 4 is an orthographic bottom view thereof; and

FIG. 5 is an isometric top, front and side view thereof.

I claim:

The ornamental design for a combination barbecue pit, grill, boiler and oven, as shown.
